UNITED STATES PATENT OFFICE.

ANDREW C. BENSON, OF CAMDEN, ARKANSAS.

GLUING-CLAMP.

No. 870,761.

Specification of Letters Patent.

Patented Nov. 12, 1907.

Application filed June 1, 1907. Serial No. 376,778.

To all whom it may concern:

Be it known that I, ANDREW C. BENSON, a citizen of the United States, residing at Camden, in the county of Ouachita and State of Arkansas, have invented a new and useful Gluing-Clamp, of which the following is a specification.

This invention relates to gluing clamps and the like and its object is to provide a durable and compact device of this character utilizing a telescopic bar whereby the same can be stored within a small compass and is therefore rendered particularly desirable for use by traveling mechanics.

Another object is to provide means whereby the bar sections can be securely locked in adjusted position and readily released so as to permit the bar to be collapsed.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of the clamp, a portion of one of the members of the bar being broken away. Fig. 2 is a section on line $x-x$, Fig. 1.

Fig. 3 is a section on line $y-y$, Fig. 1.

Referring to the figures by characters of reference, 1 designates the body of the bar A and is provided at one end with a head 2 engaged by a screw 3 which extends therethrough and is swiveled at one end to a jaw 4 formed with inwardly extending ears 5 designed to embrace and slide upon longitudinal flanges 6 located along the sides of the body 1 adjacent one face thereof. A ratchet wheel 7 is secured to the outer end of screw 3 and is disposed within the forked end 8 of a lever 9 fulcrumed upon the screw. Mounted within the fork are oppositely disposed pawls 10 held normally in engagement with the ratchet wheel 7 by means of an interposed spring 11. When the two pawls are in engagement with the ratchet wheel it is impossible to oscillate the lever without moving the screw. By throwing either of the pawls out of engagement with the ratchet, however, the lever can be oscillated so as to feed the screw in one direction. This arrangement of actuating lever, pawls and ratchet is particularly desirable when the clamp is used in cramped places where it is difficult, or impossible to swing the lever 9 in a circle.

The body 1 has a tongue 12 extending longitudinally from one end thereof and formed with longitudinal flanges 13 along opposite sides thereof. This tongue and its flanges are of less thickness than body 1 and its flanges so that shoulders are formed as shown at 14. Notches 15 are located within one edge of tongue 12 and are designed to be successively engaged by a spring pressed dog 16 pivoted within a sleeve 17. This sleeve

is mounted to slide upon the tongue 12 and has longitudinal ribs 18 disposed in alignment with the ribs 6. The spring 18 of dog 16 is designed to travel upon the body 1 and its tongue 12 so that the dog will be held at all times in contact with the tongue.

A jaw 19 is slidably mounted on sleeve 17 and carries a spring pressed dog 20 designed to engage any one of a series of notches 21 formed in sleeve 17.

It is of course to be understood that when the device is not in use the sleeve 17 can be slid longitudinally on tongue 12 until it abuts against the shoulders 14. When the sleeve is moved in this direction the dog 16 will slip over the notches 15. The normal position of the jaw 4 is close to the shoulders 14 and when so positioned the lever 9 rests close to the head 2 so that the entire device will occupy a comparatively small space and can be conveniently carried in a small tool chest or satchel. By depressing the dog 16 sleeve 17 can be drawn longitudinally upon the tongue 12 and this movement will be stopped by releasing the dog so as to enable it to engage one of the notches 15. An independent adjustment of the jaw 19 can then be effected by sliding said jaw along the sleeve 17. This movement of the jaw in one direction can be stopped by permitting the dog 20 to engage one of the notches 21. Jaw 4 can be adjusted toward or away from the jaw 19 by means of the screw 3.

It will be seen that by utilizing a telescopic bar said bar can be elongated to nearly twice its size when collapsed and therefore large articles such as furniture can be clamped within the device.

What is claimed is:

1. In a clamp the combination with a body and a tongue extending therefrom; of a sleeve slidably mounted upon the tongue, the outer faces of the sleeve being in alignment with the corresponding faces of the body, means upon the sleeve for engaging the tongue to lock the sleeve against movement in one direction, and jaws adjustably mounted upon the body and sleeve respectively.

2. In a clamp the combination with a bar comprising a body, a tongue extending from the body, and guide flanges disposed longitudinally upon the body and tongue; of a sleeve slidably mounted upon the tongue and engaging the flanges thereon, the outer faces of said sleeve being in alignment with the corresponding faces of the body, said sleeve having longitudinal guide flanges, means carried by the sleeve for engaging the tongue to lock the sleeve against movement in one direction, and jaws adjustably mounted upon the flanges of the body and sleeve respectively.

In testimony that I claim the foregoing as my own, I have hereto affixed my signature in the presence of two witnesses.

ANDREW C. BENSON.
